UNITED STATES PATENT OFFICE.

LEWIS T. WILCOX, OF PEEKSKILL, NEW YORK.

WICK-RAISING DEVICE FOR OIL-BURNERS.

1,128,740.

Specification of Letters Patent. Patented Feb. 16, 1915.

Continuation in part of application Serial No. 720,510, filed September 16, 1912. This application filed August 18, 1914. Serial No. 857,349.

To all whom it may concern:

Be it known that I, LEWIS T. WILCOX, a citizen of the United States, and a resident of Peekskill, in the county of West-
5 chester, State of New York, have invented certain new and useful Improvements in Wick-Raising Devices for Oil-Burners, of which the following is a specification.

The improvements relate to oil burners, 10 and particularly to burners adapted to burn liquid hydro-carbon through the medium of a wick, and the objects, among others, are to provide a device for raising and lowering the wick, to regulate the flame, which will 15 be of simple, inexpensive, and at the same time durable construction, and convenient and effective in operation.

So far as the improvements described and shown herein correspond with my application, 20 Serial No. 720,510, filed September 16, 1912, particularly improvements shown in Figures 13 to 16 inclusive of that application, it is my desire and intention to have the application regarded as a continuation and 25 division of said application No. 720,510. The present improvements, however, are in some important particulars an advance over the structure shown and described in the said earlier application, and may also in 30 some particulars be regarded as a carrying forward of the constructive ideas therein set forth.

The improvements are illustrated in the accompanying drawings, in which—

35 Fig. 1 is a side elevation of a wick operating device embodying the improvements. Fig. 2 is a horizontal section of the same on the line 2—2 of Fig. 1 looking in the direction indicated by the arrows in that figure. Fig. 3 is a vertical cross-section on the line 3—3 of Fig. 1 looking in the direction indicated by the arrows in that figure. Fig. 4 is a view of one of the spur wheels which engage the wick, and its connections, taken 45 on the line 4—4 of Fig. 2 and looking in the direction indicated by the arrows.

The wheel A by which the device is operated is keyed on the end of the shaft B, which rotates in the sleeve F. Fixed to this 50 shaft a short distance from the wheel A is a disk C, provided with a series of perforations C' near its periphery, and a pointer

D, loosely mounted on the said shaft, and provided with a pin D³ adapted to enter the perforations, which is pressed against the 55 disk by a spring N strung on the shaft and held under compression between the said pointer and the wheel A. The purpose of the spring is to hold the pointer D in its normal position with the pin D³ in one of 60 the holes C', so that it can only rotate with the disk and shaft, and when checked will also check the rotation of these parts. The pointer has an outer portion D' connected with the body portion by a step or bevel, 65 and this portion has an arrow point D² in a punched out aperture adapted to register with the markings E³ of the dial E to indicate the position of the wick and the resulting height of the flame.

70 The dial E is fixed on the end of the sleeve F, and is, therefore, stationary. It has a stop E' composed of a piece of its metal stamped up, and a check E² similarly formed, but capable of being depressed to 75 the level of the face of the dial so as to permit the pointer to pass it and come in contact with the stop E'. The dial also bears in connection with its markings words indicating the condition of the flame and 80 giving instructions for setting the device. As will be seen by these instructions the wick is first turned until it is level with the upper edge of the wick tube, and the pointer arm is then drawn back from the disk C, 85 thus removing the pin D³ from the peripheral recesses C', and moved until it registers with the dial marking indicating the high flame. These markings are visible through the aperture above the point D². 90 It is then released and allowed to be pressed into engagement with the disk by the spring N. Before the wick is lighted it should be turned up until it projects above the wick tube. The wheel is therefore turned clockwise 95 past the check E² and until it comes in contact with the stop E'. The wick may then be lighted easily, and turned down to high or low flame, as desired. When it is desired to extinguish the flame the wheel is 100 turned counter clockwise until the pointer comes in contact with the lower edge of the stop E'. This is a very useful and safety insuring arrangement, for the reason that

it is not necessary for the operator to see the stop E', but merely to turn the wheel until it is checked by the stop. As burners of this character are frequently operated in 5 dimly lighted places or before or after daylight, and very little illumination is provided by the blue flame, it is important to provide means for lighting, regulating and extinguishing the burner which do not require 10 visual observation in connection with their operation. The check E² will indicate to the operator when the flame is too high, and thus prevent the unusual volume of flame which results when the wick is turned above 15 the upper edge of the wick tube while the burner parts are heated. At the same time when it is desired to start the burner it is a very simple matter to press the check E down with the finger of one hand while turning 20 the wheel with the other hand, or to force the pointer to slide over the said check. By this provision the danger of producing a very high, smoky and dangerous flame by accident, as well as the danger of leaving the wick high enough to produce vapor and continue the combustion without the knowledge 25 of the operator is avoided.

The sleeve F has the end opposite the dial E secured in the housing G of the spur 30 wheels, and the shaft B extends beyond the end of the sleeve to the rear of said housing, having its end opposite the boss G² of said housing formed by stamping up a section of the rear wall. The portion B' of 35 the shaft within the housing is rectangular in cross section, and the wheels H are passed over this portion and held against rotation by the angular form of their central apertures. They are separated by the collar J 40 on the said shaft and held in position by the collar K, which extends beyond the end of the shaft and around the boss G² so as to form with the said boss a bearing for the rotation of the shaft and parts fixed thereon.

In constructing and assembling the wheels H and the adjacent parts, the wheels H and collars J and K are passed over the square 45 end of the shaft and soldered thereon so as to form with said shaft a practically integral structure. The shaft is then passed through the opening of the housing G which is surrounded by the punched-in flange G³, and the end of the collar K placed over the boss G². The sleeve F is next passed over 50 the shaft and through the said aperture of the housing until it meets the first wheel, and then soldered in the said opening from the outside of the housing. The dial E may then be fixed to the outer end of the sleeve 55 and the perforated disk C and wheel A fixed on the outer end of the shaft, with the spring N strung on the shaft and the pointer arm D loosely mounted on said shaft between them. The structure is now complete 60 and ready to be applied to the wick tube by 65

soldering the flanges around the open side of the housing thereto and applying a suitable brace or bracket, if desired, or by any other satisfactory method.

The wheels H pass through the outer shell 70 of the wick tube L and engage the wick M in the usual manner, the said wick being provided with the ordinary perforated metal reinforcement O at this point.

In moving the pointer D a leverage is 75 afforded by the extending portion D', the opposite end of the pointer arm being the fulcrum and the spring the weight. This enables the manufacturer to use a relatively powerful spring which will hold the pointer 80 arm securely in its normal position.

What I claim is:

1. In a device of the character described, the combination of a rotatable shaft, means secured thereon for moving the wick 85 through the rotation of the shaft and an indicator comprising a member fixed to the shaft and pointer mounted to rotate on said shaft, a connection between the pointer and member and means for automatically causing the same to connect the said pointer with the said member at different points, whereby the former may be secured thereto in different positions, and a dial fixed with respect to the said pointer for indicating the position 90 of the wick.

2. In a device of the character described, the combination of a rotatable shaft, means secured thereon for moving the wick through the rotation of the shaft and an indicator comprising a member fixed to the shaft and pointer mounted to rotate on said shaft, a connection between the pointer and member whereby the former may be secured thereto in different positions and a dial fixed with respect to the said pointer for indicating the position of the wick, a stop on said dial whereby the rotation of the shaft is checked at a predetermined 100 point through contact with the pointer therewith while engaged with the said member, and means for removably holding the pointer in engagement with the said member and in the path of the stop, said means permitting disengagement of the said parts 105 by pressure on one of them.

3. In a device of the character described, the combination of a rotatable shaft, means secured thereon for moving the wick through the rotation of the shaft and an indicator comprising a plate fixed to the shaft and pointer mounted to rotate on said shaft, a connection between the pointer and plate whereby the former may be secured thereto in different positions and a dial fixed 115 with respect to the said pointer for indicating the position of the wick, a stop on said dial whereby the rotation of the shaft is checked at a predetermined point through contact with the pointer therewith while 120 125 130

engaged with the plate, and means for removably holding the pointer in engagement with the plate and in the path of the stop, and a checking device in the path of the pointer, removed from said stop said checking device being movable out of the path of the pointer.

4. In a device of the character described, the combination of a rotatable shaft, means secured thereon for moving the wick through the rotation of the shaft and an indicator comprising a plate fixed to the shaft and pointer mounted to rotate on said shaft, a connection between the pointer and plate whereby the former may be secured thereto in different positions and a dial fixed with respect to the said pointer for indicating the position of the wick, a stop on said dial whereby the rotation of the shaft is checked at a predetermined point through contact with the pointer therewith while engaged with the plate, and means for removably holding the pointer in engagement with the plate and in the path of the stop, and a checking device in the path of the pointer, removed from said stop said checking device being movable out of the path of the pointer.

5. In a device of the character described, the combination of a shaft, means for rotating the shaft, means secured to said shaft for raising and lowering the wick by the rotation of the shaft and a housing for the said wick moving means and one end of the shaft, comprising a shell mounted adjacent to the wick, an opening therein through which the shaft extends, a boss in said housing, a collar secured to and extending beyond said shaft and surrounding the said boss, the end of the shaft being adjacent to the said boss.

6. In a device of the character described, the combination of a rotatable shaft, means connected therewith for moving the wick, and an indicator comprising a member in fixed relation to the shaft and a pointer mounted to move with said shaft, a connection whereby the pointer may be secured to the said member in different positions, a dial fixed with respect to the said pointer for indicating the position of the wick, and a stop in fixed relation to said dial, whereby the rotation of the shaft is checked at a predetermined point through contact of the pointer with the stop while engaged with the said member, means for holding the pointer in engagement with the said member and in the path of the stop, and a checking device in the path of the pointer removed from said stop, one of said parts being movable out of the path of the other.

7. The combination of a wick raising shaft, means carried thereby for engaging the wick, whereby movement of the shaft causes the wick to be raised and lowered, a

device fixed to the said shaft and movable therewith, a check in the path of said device in which it moves with the shaft, and a stop also in the path of said device.

8. The combination of a wick raising shaft, means carried thereby for engaging the wick, whereby movement of the shaft causes the wick to be raised and lowered, a device fixed to the said shaft and movable therewith, a check in the path of said device in which it moves with the shaft, and a stop also in the path of said device, the said device and check being disengageable without disconnecting the former from the shaft.

9. The combination of a wick raising shaft, means carried thereby for engaging the wick, whereby movement of the shaft causes the wick to be raised and lowered, a device fixed to the said shaft and movable therewith, the said device which is movable with the shaft being capable of movement relative to the wick operating movements of the shaft while in one position and held against said movement in another position, and means for automatically returning it to the second position.

10. The combination of a wick raising shaft, means carried thereby for engaging the wick, whereby movement of the shaft causes the wick to be raised and lowered, a device fixed to the said shaft and movable therewith, the said device which is movable with the shaft being capable of movement relative to the wick operating movements of the shaft while in one position and held against said movement in another position, and means for automatically returning it to the second position, said means comprising a spring bearing against said device and pressing it constantly toward the said second position.

11. The combination of a wick raising shaft, means carried thereby for engaging the wick, whereby movement of the shaft causes the wick to be raised and lowered, a device fixed to the said shaft and movable therewith, the said device which is movable with the shaft being capable of movement relative to the wick operating movements of the shaft while in one position and held against said movement in another position, and means for automatically returning it to the second position, said means comprising a spring bearing against said device and pressing it constantly toward the said second position, and a member fixed to the shaft adjacent to the said device, provided with a series of recesses and said device being provided with a portion adapted to engage said recesses successively.

12. In a device of the character described, the combination of a shaft, means connected therewith for raising and lowering the wick through the rotation of the shaft, a housing

for one end of the shaft adjacent to the wick, said shaft having a hollow end and said housing having a boss entering said hollow end, whereby the said end of the shaft is provided with a bearing and held against lateral movement.

5 Witness my hand this 29th day of July,

1914, at the city of New York, in the county and State of New York.
